TREATMENT OF TERPENE ALCOHOL-ALKALI METAL BISULPHITE REACTION PRODUCTS

Robert C. Palmer and Henry J. Warmuth, Pensacola, Fla., assignors to Newport Industries, Inc., Pensacola, Fla., a corporation of Delaware

No Drawing. Application August 24, 1936,
Serial No. 97,658

6 Claims. (Cl. 260—159)

This invention relates to the treatment of reaction products obtained by reacting terpene alcohols with alkali metal bisulphites to convert such reaction products into compounds having good wetting and detergent properties.

More specifically this invention relates to the pyrolysis of terpene alcohol-alkali metal bisulphite reaction products to form new compounds having good wetting and detergent properties.

It is known that unsaturated aliphatic or cyclic terpene alcohols such as geraneol, linalool, the terpineols and the like will react with alkali metal bisulphites such as for example, sodium or potassium acid sulphites. The reaction products obtained are water soluble and are believed to be alkali metal salts of the sulphonic acids of the terpene alcohols.

It is also known that there terpene alcohols such as terpineols and the like possess strong wetting and detergent properties but have very low solubility in water and must be reduced to a colloidal state by means of soaps and the like to utilize these properties. It might be expected therefore that the water soluble reaction products of the terpene alcohols and alkali metal bisulphites would have even better wetting and detergent properties than the terpene alcohols themselves. However, such reaction products possess practically none of these wetting and detergent properties.

We have now found that the water soluble reaction products of terpene alcohols and alkali metal bisulphites readily undergo a fairly low temperature pyrolysis to yield new products which have excellent wetting and detergent properties especially in the presence of strong acids.

The new products are reddish brown viscous liquids, acidic in character, and can be neutralized with alkali metals to lemon yellow colored compounds. The new products have a slight terpene odor, nitrate readily, couple with diazotized amino compounds, react with solutions of salts of the heavy metals, are quantitatively precipitated by aluminum salts, and have good wetting and detergent qualities in the presence of strong acids. The wetting qualities of these new compounds in the presence of an alkali are somewhat poorer than in solutions having a pH value below 5. Nevertheless, the wetting properties of these new compounds even in the presence of an alkali are much greater than the wetting properties of the original terpene alcohol-alkali metal bisulphite reaction products.

It is, then, an object of this invention to prepare wetting and detergent agents from the re-

action products of terpene alcohols and alkali metal bisulphites.

A further object of this invention is to convert terpene alcohol-alkali metal bisulphite reaction products into new compounds having good wetting and detergent properties.

A further object of this invention is to pyrolyze terpene alcohol-alkali metal bisulphite reaction products.

A further object of this invention is to prepare wetting and detergent agents by pyrolysis of the reaction products of a terpene alcohol and an alkali metal bisulphite.

Other and further objects of this invention will become apparent to those skilled in the art from the following example and detailed description of a preferred form of the invention.

Preferred process of preparing terpene alcohol-alkali metal bisulphite reaction products

It is known that terpene alcohols such as, for example, alpha terpineol, will react with a dilute solution of sodium bisulphite in water if a large excess of the sodium bisulphite is used.

We prefer to prepare the reaction product, however, with an excess of the terpene alcohol present in the reaction mixture as follows: In any type of vessel, either open or closed, are charged 1500 parts of water, 100 parts of technical grade sodium bisulphite and 150 parts of alpha terpineol or a suitable mixture of solvents containing 150 parts of alpha terpineol, and/or other terpene alcohols. Steam distilled pine oil containing 50 to 60% or more of tertiary terpene alcohols is a suitable starting material.

The ingredients in the vessel are agitated at a temperature of 40 to 45° C. until a clear solution is obtained. Similar additional portions of reactants are then added to the vessel and the process is repeated. The process is repeated twice more by the addition of two separate portions of reacting ingredients. At the end of this time there are approximately 1000 parts of reaction product dissolved in 1500 parts of water, plus unreacted alpha terpineol and/or other terpene alcohols which are now in solution, plus a small amount of unreacted sodium bisulphite and any impurities. The length of time of agitation for each batch of added ingredients is about two hours when a technical grade of sodium bisulphite is used.

The contents of the vessel are then subjected to steam distillation and the greater portion of the excess terpineol and any other unreacted portions of the starting oil are recovered. When the

- concentration of the reaction product becomes from 55 to 60%, a precipitation of unreacted in-
organic material results. The distillation is then stopped, the inorganic material filtered off and
5 the remaining reaction product in solution is ad-
justed by the addition of water to a concentra-
tion of about 55% by weight. This gives a maximum
concentration of product which will not
tend to crystallize at room temperature.
10 The 55% solution of terpene alcohol-sodium
bisulphite reaction products may then be used as
the starting material for the preparation of the
novel pyrolyzed compounds according to this in-
vention.
15 *Preparation of pyrolyzed terpineol-sodium bisul-
phite reaction products*

To 700 parts of terpineol-sodium bisulphite re-
action products of about 55% concentration in
20 water are added 180 parts of 77% sulphuric acid.
The mixture is heated gradually, preferably in a
closed system, and as the heat increases, water
is evolved as well as sulphur dioxide and a ter-
pene hydrocarbon oil. The reaction is controlled
25 by measuring the amount of water distilled from
the boiling mass. When 140 parts of water have
been distilled, the mixture in the still becomes
cloudy and separates into two layers. The top layer
30 contains practically all of the organic matter,
some water and sodium bisulphite. The bottom
layer consists principally of water and sodium bi-
sulphite with practically no organic matter. By
the time 250 parts of water have been distilled off,
35 a separation of these two layers should be made by
drawing off the lower layer. The top layer is
subjected to further heating until 45 additional
parts of water have been distilled and the tem-
perature in the liquid is about, but does not exceed
128° C.

40 A second separation of sodium bisulphite solu-
tion is made at this point and the top layer set
aside for further processing.

It is preferred to make two separations of the
water solution of sodium bisulphite because the
45 amount of material to be separated reaches a
maximum at the time 250 parts of water have been
distilled off and thus a separation is made at this
point in order to remove the greatest volume at
one time. If the separation is attempted in one
50 step at the end of the reaction, it is found that
the control as evidenced by the amount of water
distilled off is no longer a guide of the progress of
the reaction. Furthermore, in this event, the
final product is found to contain a larger amount
55 of sodium bisulphite and requires more alkali to
neutralize it, thus giving a poor quality product
because of salt adulteration. At the end of the
reaction as specified above there have been pro-
duced quantities of materials approximately as
60 follows:

- 47 parts sulphur dioxide
- 32 parts terpene hydrocarbon oil
- 260 parts sodium bisulphite solution of which
65 approximately
- 108 parts is sodium bisulphite and
- 152 parts is water
- 250 parts of the desired final product contain-
ing approximately
- 70 63 parts of sodium bisulphite but practically
no water
- 250 parts of water which has been distilled off
during the reaction.

The sulphur dioxide produced may vary from
75 30 parts to 94 parts; the terpene hydrocarbon oil

may vary from 26 parts to 56 parts; and the
amount of water may be increased or decreased,
but the amount of sodium bisulphite solution
formed should remain relatively constant.

A variation of several factors, such as the
strength of acid, concentration of terpineol-sodium
bisulphite reaction product, final temperature
of the reaction and rate of distillation will change
the approximate quantities of some of the mate-
rials produced by the reaction, but without great-
ly changing the most important property of the
final product, viz., its wetting power.

The purpose of adding acid to the reaction
product of the terpene alcohol and alkali metal
bisulphite is to convert the reaction product into
its acid form, since then the pyrolysis step pro-
ceeds smoothly to the desired final product. The
pyrolysis does not proceed so satisfactorily if a
free strong acid is present. Consequently, we use
only sufficient sulphuric acid to form the acid
salt, viz. sodium bisulphate. We have found that
the acid salt is less soluble in the reaction mass
than the neutral sulphate and therefore its for-
mation enables us to obtain a product more nearly
free from inorganic salts. If other acids, such as
hydrochloric or phosphoric, were used in place
of sulphuric acid, they should be used in amounts
only sufficient to produce the corresponding alkali
metal salts by combination with the alkali metal
of the reaction product. Preferably, no free
strong acid is present in the reaction mass, but
the scope of our invention does not exclude that
possibility.

The use of very dilute acids is not so practical,
since such use necessitates the evaporation of
more water before it is possible to reach the tem-
perature at atmospheric pressure where the py-
rolysis reaction proceeds most readily. We
therefore prefer to use a relatively concentrated
mineral acid in the acidification step prior to
pyrolysis.

The final temperature should not exceed 128°

C. Higher temperatures cause rapid destruc-
tion of the product, converting it into water insol-
uble tar-like materials having little, if any, wet-
ting power.

The product of the above reaction may be neu-
tralized by any of the caustic alkalis or alkaline
earth metal hydroxides, but sodium or ammonium
hydroxide is preferably used because the salts
produced have a greater solubility in water.

In order to produce approximately a 60% water
solution of the sodium salt of the product, there
are added to 250 parts of the product obtained
as described in the above example, 188 parts of 29
Bé. caustic soda solution (about 22% alkali).
55 This yields a lemon yellow solution which can be
readily handled and which is readily soluble in
water. By the Clarkson-Draves wetting speed
test, 0.35 part of this solution in 100 parts of
water will wet in 25 seconds or less, in the pres-
ence of any strongly ionizable acid at 40° C. The
amount of free acidity is relatively unimportant.
Even 5% of free sulphuric acid does not impair
the efficiency of the wetting speed of the com-
pound.

60 From the above description it should be under-
stood that this invention provides a method for
the production of novel pyrolyzed products by
acidifying and heating a terpene alcohol-alkali
metal bisulphite reaction product. During this
heat treatment, sulphur dioxide, a terpene hy-
drocarbon oil, sodium bisulphite solution, the
novel pyrolyzed product and water are obtained.

The pyrolyzed product can be used as such as
a wetting agent or detergent or can be con-
75

verted into a caustic alkali metal or an alkaline earth metal salt, which are also water soluble and form excellent wetting agents or detergent material. Both the pyrolyzed product and its water soluble alkali metal and alkaline earth metal salts are also good emulsifying and dispersing agents. For instance, a 60% concentration of the pyrolyzed product, or of any of its water soluble salts, in aqueous solution, enables the formation of clear solutions with ordinarily water immiscible liquids, such as vegetable oils, fatty acids, petroleum hydrocarbons, esters, ketones, terpene hydrocarbons, alcohols, natural resins, and the like. The clear solutions so formed, upon dilution with water, become stable emulsions or dispersions which may have a wide variety of uses.

The pyrolyzed product and its salts may, therefore, be used to advantage as emulsifying agents for water insoluble wetting agents like steam distilled pine oil, or terpineol, particularly so since it is possible to make both acid and alkaline emulsions that have stable characteristics. A large variety of other uses may be mentioned, including the use of the pyrolyzed product and its salts in the manufacture of lubricants, polishes, insecticides, emulsified coating compositions, cleaning and scouring compositions, waterproofing emulsions, and many others.

We are aware that numerous details of the process may be varied through a wide range without departing from the principles of this invention, and we, therefore, do not purpose limiting the patent granted hereon otherwise than necessitated by the prior art.

35 We claim as our invention:

1. The process of preparing wetting agents from terpene alcohol-alkali metal bisulphite reaction products which comprises heating the acid forms of said products at a temperature of not over 128° C. to distill off water therefrom until the mixture separates into two layers, and recovering the top layer.

2. The process of converting a terpene alcohol-alkali metal bisulphite reaction product into a wetting agent which comprises heating an aqueous solution of said reaction product at a temperature of not over 128° C. in the presence of sufficient acid to combine with the alkali metal of said reaction product to distill off water from the reacting mixture until the mixture separates into two layers, and recovering the top layer.

3. The process of preparing wetting agents which comprises preparing a mixture of an aqueous solution of a terpineol-alkali metal bisulphite reaction product and sufficient acid to combine with the alkali metal of said reaction product, heating said mixture to distill off water from said mixture until the mixture separates into two layers, drawing off the lower layer, subjecting the top layer to a further heat treatment to distill off more water therefrom, permitting the mixture to separate again into two layers and recovering the top layer, the heating and distillation steps being carried out at a temperature not over 128° C.

4. The process of preparing wetting and detergent materials which comprises heating a mixture of 700 parts of a terpineol-sodium bisulphite reaction compound of about 55% concentration in water and the equivalent of about 180 parts of 77% sulphuric acid, allowing sulphur dioxide, 20 a terpene hydrocarbon oil and water to be distilled from the mixture until the mixture separates into two layers, drawing off the bottom layer, further heating the top layer to distill off more water therefrom, allowing the mixture to separate again into two layers and recovering the top layer containing the wetting and detergent material, the heating and distillation steps being carried out at a temperature not over 128° C.

5. The process of making wetting and detergent material which comprises heating together 700 parts of a 55% aqueous solution of a terpineol-sodium bisulphite reaction product and the equivalent of 180 parts of 77% sulphuric acid, distilling off 250 parts of water from the mixture 30 at atmospheric pressure until the mixture separates into two layers, drawing off the lower layer, further heating the upper layer at atmospheric pressure to distill off 45 additional parts of water therefrom, again allowing the mixture to separate into two layers, and recovering the layer containing the pyrolyzed terpineol-sodium bisulphite reaction product.

6. The process according to claim 5 in which the pyrolyzed product is reacted with an alkali hydroxide selected from the class consisting of alkali metal and alkaline earth metal hydroxides to produce a lemon yellow colored solution which is soluble in water.

ROBERT C. PALMER. 50
HENRY J. WARMUTH.
